GAS LIFT APPARATUS

Thomas E. Bryan, Oklahoma City, Okla.

Application December 21, 1936, Serial No. 117,982

13 Claims. (Cl. 103—234)

This invention relates to an improvement in apparatus for removing liquids from wells or the like, and more specifically for removing oil from oil wells by means of gas or air under pressure. For the purposes of the following specification and claims, the term "gas" will be used as meaning any gaseous substance suitable for the purpose set forth, whether said substance be of that class of gases known as "natural gas", or whether it be atmospheric or some other composition.

In the past oil has been removed from oil wells and other liquids from similar wells by means of introducing into the well first a casing, the lower end of which may be positioned at some desired point either above or below the liquid level in the well, and a tubing within said casing, which tubing is lowered to a point substantially below the liquid level in the well.

Various arrangements have been resorted to for supplying the gas under pressure to the inside of the casing in an apparatus thus set up, and this gas under pressure has been utilized in a variety of ways for causing the liquid to rise from the bottom of the well through the tubing to the top of the well. Perhaps the simplest arrangement to this end has been that employed in some instances where the gas has simply been allowed to exert a pressure upon the upper surface of the liquid within the well, and thus cause the liquid to rise within the tubing. This, however, is very limited in its application for a number of reasons, and various types of valves have been employed for admitting the gas under pressure through the walls of the tubing at various points so that such gas might aerate the liquid standing within the tubing and make the standing column of liquid lighter. In many instances it is possible to make the liquid sufficiently lighter so that the formation pressure within the well will be enabled to lift the column of liquid from the well hole through the tubing. Such valves as this are commonly known as "kick-off valves".

In still other instances, these valves have been so constructed that a large quantity of gas will be admitted to the tubing at a point below the liquid level therein so as to form a slug or piston composed of gas under high pressure, and to continue the admission of such gas until the piston expands and causes the liquid above it to be forced out of the well.

All of the foregoing arrangements have their advantages and most of them have certain disadvantages. It is an object of this invention to provide an arrangement utilizing a combination of the last two forms of apparatus for the pur-

pose of eliminating certain disadvantages inherent in each, while retaining the advantages of both.

In the past also it has been customary to provide the valves such as above mentioned, and to permanently attach them to the tubing before it is lowered into place within the well. However, many wells do not require the use of these valves until the well has been in production for a considerable period of time. Furthermore, where only a single valve is used for admitting a slug of gas to the tubing to force the liquid therefrom, this valve will in use become worn and may be damaged in various ways so as to become no longer useful. Under those circumstances, it has previously been necessary to pull the entire tubing from the well so that the valve adjacent the lower end thereof might be removed and repaired or replaced.

It is an object of this invention to provide a means whereby a valve for admitting gas to a tubing may be removed from or replaced in the tubing without the necessity of removing the tubing from the well.

It is a further object to provide a housing for such a valve which may be removed and replaced without removing the tubing from the well.

It is a further object to provide a means within a tubing for removably seating a valve device so that it may be removed from or replaced in the tubing without the necessity of withdrawing the tubing from the well, and so that when in place within the well it will control communication between the outside and the inside of the tubing.

It is a further object to provide a combination for accomplishing the objects above set forth in which the gas about the tubing will be prevented from exerting any pressure upon the upper surface of the liquid within the well.

Other objects and advantages of this invention will become apparent from the following description taken in connection with the accompanying drawings. It is to be understood that said drawings and description are by way of illustration and example, and that this invention is to be limited only by the prior art and by the terms of the appended claims.

In the drawings:

Fig. 1 is an assembly view in vertical cross section of an apparatus constructed in accordance with this invention in place within a well.

Fig. 2 is a view in vertical cross section illustrating the kick-off valves employed in connection with this apparatus, together with the means of mounting the same on the tubing.

Fig. 3 is a vertical cross section illustrating an ⁵ intervening valve used in connection with this invention, together with the manner of mounting the same within the tubing.

Fig. 4 is a side elevation of the housing within which said intervening valve is mounted.

Fig. 5 is an enlarged vertical cross section illustrating the intervening valve used in connection with this invention.

Referring more specifically to Fig. 1, it will be seen that in the well illustrated there is a casing 1 which is lowered within the well to substantially the top of the producing formation 2, in which position its lower end is below the level of the liquid 3 within the well.

Within the casing 1 there is lowered a tubing 4, this tubing being lowered a substantial distance below the lower end of the casing so that its lower end is substantially below the top of the producing formation 2.

At spaced intervals, the tubing is provided with special fittings 5 which are adapted to receive kickoff valves in a manner presently to be set forth. Below these special fittings 5 the tubing is also provided with a coupling member 6 adapted to be threaded at its opposite ends to the adjacent sections of tubing 4 and provided with threads 7 for that purpose. Intermediate its threaded end portions this coupling 6 is provided with an interval unthreaded downwardly converging tapered zone 8 which is adapted to form a seat for a housing 9 containing an intervening valve, as will be presently set forth.

At the lower end of the annular space formed between the tubing and the casing, this space is closed by means of a packer element 10 so that the annular space designated by the numeral 11 may be filled with gas under pressure. The space within the tubing 4 which is designated by the numeral 12 is to be utilized for flowing the liquid from the well. Suitable connections (not shown) will be made at the top of the casing and tubing so that gas under pressure may be supplied to the casing, and so that liquid flowing from the tubing 45 may be properly conducted to tanks or the like for receiving the same.

The kickoff valves which are disposed within the special fittings 5 are of the type set forth in my co-pending application Serial No. 103,824. The fittings 5 are also described in said application, as well as the manner in which this valve functions.

It is to be noted that the fittings 5 provide an unobstructed passageway in alignment with the remainder of the tubing, and that each also provides a chamber in communication with this passageway through an opening 13 within which chamber the kickoff valve is located. This kickoff valve consists of a cylindrical member 14 within which are provided a pair of downwardly facing valve seats 15 and 16. Intermediate these valve seats 15 and 16 there is an opening through a side wall of the cylindrical member adapted to register with a similar opening through an outer wall of the chamber 13, so that the interior of the cylindrical member will be at all times in communication with the exterior of the tubing.

Within the cylindrical member 14 there is slidably mounted a valve stem 17 having upper and lower valve elements 18 and 19 thereon adapted to seat against the corresponding valve seats 15 and 16. The valve stem is normally held in its lower position by means of a spring 20 surrounding its lower end and bearing against a nut or the like 21 fixed upon the lower end of the valve stem. The

upper end of this spring 20 bears against the lower end of a member 22, which is connected with the lower end of the cylindrical member 14. It is to be noted that the upper valve seat and valve element 15 and 18, respectively, are larger in diameter than the lower valve seat and valve element 16 and 19, respectively.

In operation it will be seen that the kickoff valve just described will be normally open, and will be constantly urged to open position by means of the spring 20. It will further be seen that when the pressure within the tubing falls to a sufficiently low value, the velocity with which the gas will pass in through the valve will exert an unbalanced influence upon the valve and eventually cause it to close. It will be held in closed position because of unequal size of the valve elements until such time as the pressure within the tubing again rises to a value which combined with the effect of the spring 20 will cause the valve to open.

Referring now to Figs. 3, 4 and 5, it will be seen that the lower valve, which will be termed an intervening valve because of its intermittent action, is arranged similarly to the kickoff valve above described, but differs therefrom in certain important respects, this intervening valve being of the type set forth in my co-pending application Serial No. 97,511.

Like the kickoff valve above described, this intervening valve consists of a cylindrical member 14 having upper and lower valve seats 15 and 16 with a lateral opening through the cylindrical member intermediate these valve seats. A valve stem 17 having valve elements 18 and 19 thereon adapted to seat against the aforesaid valve seats, respectively, is also provided, this valve stem preferably having a guide member 23 upon its upper end. In addition, there is provided a third valve seat member 24 against which a valve element 25 is adapted to seat.

Secured to the lower end of the cylindrical member 14 is a chamber 26 within which is disposed on the lower end of the valve stem 17 and below the valve element 25 a pressure sensitive diaphragm 27 within which may be placed a compression spring 28. Under certain circumstances the pressure diaphragm may be made in such a manner that it will exert the necessary force in an upward direction on the valve stem 17, and thus render unnecessary the presence of the spring 28. It will be seen that the valve just described differs in its operation from the kickoff valve above mentioned in that it is normally closed, whereas said kickoff valve is normally open. Further, the valved openings or seat members in the last described valve are larger and capable of conducting more gas into the tubing than are those utilized by the kickoff valves. Similarly, the lateral opening into the cylindrical member 14 of the last mentioned valve is materially larger than that into the kickoff valve previously described.

The valve which has just been described is mounted within a housing which is best illustrated in Figs. 3 and 4. A nipple 29 connects the lateral opening in the cylindrical member 14 with a corresponding opening in the side wall of the housing, and the valve assembly is mounted within the housing by means of this connection, and by means of a lower supporting connection illustrated at 30 in Fig. 5.

It will be seen that the exterior surface of the housing 9 is tapered as previously described to seat within the collar 6 of the tubing, and that it

is formed with a circumferential groove 31 thereabout at the position of the lateral opening through the housing. The coupling 6 is likewise provided with a lateral opening 32 at such a level that when the housing 8 is seated within the coupling 6 the groove 31 and the lateral opening in the housing will register with the lateral opening 32 in the coupling. Thus, the interior of the cylindrical member 14 of the valve within the housing 8 will be in direct communication with the exterior of the tubing.

It is further to be noted that the housing 8 is open at its lower end as at 33, and is provided at its upper end with openings 34 so that liquid may pass freely therethrough when it is in its place within the coupling 6. Extending upwardly above the openings 34 is a spear connection 35 adapted to receive an overshot or similar fishing tool which may be lowered into the well for the purpose of removing the housing 8 and its contained valve from the tubing.

From the foregoing it will be seen that under ordinary conditions of operation, the upper valves which have been designated as kick-off valves, 25 will first admit a gas into the tubing to move such liquid as may lie above these valves, and that the diaphragm valve which has been termed an intermitting valve will then act as a pump for admitting successive slugs of gas into the tubing so as 30 to remove the fluid as it comes into the well tubing. It is to be noted that the manner of mounting the kick-off valves is such that the tubing is open from its upper end downwardly to the position of the diaphragm valve. This makes it possible to either lower or drop the housing containing the diaphragm or intermitting valve into 35 position from the upper end of the tubing while the tubing is in place within the well, and whenever desired to lower a line or cable into the well 40 with a suitable fishing tool on the lower end thereof to engage the element 36 of the housing, and by this means to remove the housing from the well without removal of the tubing.

It will be seen from the foregoing that a means 45 has been provided for carrying out all the objects and advantages sought by this invention.

I claim:

1. In a device for raising fluid from a well, in combination, a pair of conduits in said well, one 50 of said conduits being adapted to contain a gas under pressure and the other of said conduits being adapted to conduct a liquid from said well, a plurality of normally open valves at spaced intervals along said conduits for controlling communication therebetween, said valves being adapted to be closed by a predetermined flow of gas from said gas containing conduit into said liquid conduit, and a normally closed valve below 55 said first mentioned valves for controlling communication between said gas containing conduit and said liquid conduit, said last mentioned valve being adapted to be opened by a predetermined pressure within said liquid conduit and adapted to remain open until the pressure within said liquid conduit falls to a predetermined value lower than said pressure at which said valve will open, said liquid conduit being disposed within 60 said gas containing conduit and said gas containing conduit being closed at its lower end.

2. In a device for raising fluid from a well, in combination, a pair of conduits in said well, one of said conduits being adapted to contain a gas under pressure and the other of said conduits being adapted to conduct a liquid from said well, a plurality of normally open valves at spaced in-

tervals along said conduits for controlling communication therebetween, said valves being adapted to be closed by a predetermined flow of gas from said gas containing conduit into said liquid conduit, and a normally closed valve below 5 said first mentioned valves for controlling communication between said gas containing conduit and said liquid conduit, said last mentioned valve being adapted to be opened by a predetermined pressure within said liquid conduit and adapted to remain open until the pressure within said liquid conduit falls to a predetermined value lower than said pressure at which said valve will open.

3. In a device for raising fluid from a well, in combination, a pair of conduits in said well, one of said conduits being adapted to contain a gas under pressure and the other of said conduits being adapted to conduct a liquid from said well, a plurality of normally open valves at spaced intervals along said conduits for controlling communication therebetween, and a normally closed valve below said first mentioned valves for controlling communication between said gas containing conduit and said liquid conduit, said last mentioned valve being adapted to be opened by a predetermined pressure within said liquid conduit and adapted to remain open until the pressure within said liquid conduit falls to a predetermined value lower than said pressure at which said valve will open.

4. In a device for raising a liquid from a well, in combination, a pair of conduits extending into said well, one of said conduits being adapted to contain a gas under pressure and the other of said conduits being adapted to conduct a liquid from said well, said other conduit having a downwardly converging tapered portion therein adapted to form a seat for a valve housing, and having a lateral opening through said seat in communication with the interior of said one conduit, and an externally tapered valve housing adapted to be moved through said other conduit to seat against said seat, said valve housing having openings at the upper and lower ends thereof and having a lateral opening adapted to register with the lateral opening of said other conduit when said housing is seated upon said seat, and having means at its upper end whereby it may be removed from said other conduit, and a valve within said housing for controlling passage through said opening in the side wall of the said other conduit and said opening in the valve housing.

5. In a device for raising a liquid from a well, in combination, a pair of conduits extending into said well, one of said conduits being adapted to contain a gas under pressure and the other of said conduits being adapted to conduct a liquid from said well, said other conduit having an upwardly facing seat therein adapted to receive a valve housing, and having a lateral opening through said seat in communication with the interior of said one conduit, a valve housing adapted to be moved through said other conduit to seat against said seat, said valve housing having openings at the upper and lower ends thereof and having a lateral opening adapted to register with the lateral opening of said other conduit when said housing is seated upon said seat, and having means at its upper end whereby it may be removed from said other conduit, and a valve within said housing for controlling passage through said opening in the side wall of the said other conduit and said opening in the valve housing.

6. In a device for raising a liquid from a well,

in combination, one conduit adapted to contain a gas under pressure and another conduit adapted to conduct a liquid from said well, said other conduit having an upwardly facing seat therein adapted to receive a valve housing, and having an opening through said seat into said one conduit, and a valve housing movable through said other conduit to seat against said seat and having openings at the upper and lower ends thereof and an opening through its side wall adapted to register with the opening through the side wall of said other conduit, and a valve within said housing for controlling passage through said opening in the side wall of the said other conduit and said opening in the valve housing.

7. In a device for raising a liquid from a well, in combination, one conduit adapted to contain a gas under pressure and another conduit adapted to conduct a liquid from said well, said other conduit having an upwardly facing seat therein adapted to receive a valve housing, and having an opening through said seat into said one conduit, and a valve housing movable through said other conduit to seat against said seat and having openings at the upper and lower ends thereof and an opening through its side wall adapted to register with the opening through the side wall of said other conduit, and having means at its upper end whereby it may be removed from said other conduit.

8. In a device for raising a liquid from a well, in combination, one conduit adapted to contain a gas under pressure and another conduit adapted to conduct a liquid from said well, said other conduit having an upwardly facing seat therein adapted to receive a valve housing, and having an opening through said seat into said one conduit, and a valve housing movable through said other conduit to seat against said seat and having openings at the upper and lower ends thereof and an opening through its side wall adapted to register with the opening through the side wall of said other conduit.

9. In combination with a conduit for removing liquid from a well, said conduit having a lateral opening therein in communication with a source of gas under pressure, a valve adapted to be lowered into said conduit for controlling flow through said opening and having a part adapted to removably seat within said conduit and to form a sealed connection with the inner end of said opening when so seated.

10. In a valve assembly for controlling the admission of gas under pressure into a liquid column, a housing having an externally tapered surface convergent downwardly and having an opening through one of its side walls, and inlet and outlet openings at its lower and upper ends, respectively, and a normally closed valve means mounted within said housing for controlling ingress to said housing through said lateral opening, said valve means being arranged to be opened by a predetermined pressure of fluid within said housing, and to close only after the pressure within said housing has fallen to a predetermined value lower than the pressure required to open said valve.

11. In a valve assembly for controlling the admission of gas under pressure into a liquid column, a housing having an external seating surface and having a lateral opening through said surface, and inlet and outlet openings at its lower and upper ends, respectively, and a normally closed valve means mounted within said housing for controlling ingress to said housing through said lateral opening, said valve means being arranged to be opened by a predetermined pressure of fluid within said housing, and to close only after the pressure within said housing has fallen to a predetermined value lower than the pressure required to open said valve.

12. In a valve assembly for controlling the admission of gas under pressure into a liquid column, a housing having an external seating surface and having a lateral opening through said surface, and inlet and outlet openings at its lower and upper ends, respectively, and a valve means mounted within said housing for controlling ingress to said housing through said lateral opening, said valve means being arranged to be opened by a predetermined pressure of fluid within said housing, and to close only after the pressure within said housing has fallen to a predetermined value lower than the pressure required to open said valve.

13. In a valve assembly for controlling the admission of gas under pressure into a liquid column, a housing having an external seating surface and having a lateral opening through said surface, and inlet and outlet openings at its lower and upper ends, respectively, and a valve means mounted within said housing for controlling ingress to said housing through said lateral opening.

THOMAS E. BRYAN.
